UNITED STATES PATENT OFFICE
CERTIFICATE OF CORRECTION

Design No. 211,073

May 14, 1968

William C. Christine et al.

It is hereby certified that error appears in the above numbered patent requiring correction and that the said Letters Patent should read as corrected below.

In the grant, lines 2 to 4, "assignors to Allen Electronics, Inc., of Bethlehem, Pennsylvania, a corporation of Pennsylvania" should read -- assignors, by mesne assignments, to A. E. I. Corporation, of Bethlehem, Pennsylvania, a corporation of Delaware --; line 14, "Allen Electronics, Inc., its successors" should read -- A. E. I. Corporation, its successors --. In the heading to the drawings and printed specification, lines 5 and 6, "assignors to Allen Electronics, Inc., Bethlehem, Pa., a corporation of Pennsylvania" should read -- assignors, by mesne assignments, to A. E. I. Corporation, Bethlehem, Pa., a corporation of Delaware --.

Signed and sealed this 23rd day of September 1969.
